UNITED STATES PATENT OFFICE.

LAURENCE HUSTON KIRK, OF HAVRE DE GRACE, MARYLAND, ASSIGNOR TO GORRELL STEEL SPIKE LOCK RAILROAD TIE CORPORATION, OF HAVRE DE GRACE, MARYLAND, A CORPORATION OF MARYLAND.

SPIKE-FASTENING MEANS.

1,115,438.

Specification of Letters Patent. Patented Oct. 27, 1914.

Application filed August 31, 1914. Serial No. 859,513.

To all whom it may concern:

Be it known that I, LAURENCE H. KIRK, a citizen of the United States, residing at Havre de Grace, in the county of Harford and State of Maryland, have invented certain new and useful Improvements in Spike-Fastening Means, of which the following is a specification.

My invention relates to a fastening means composed, essentially, of two co-acting parts; one of said parts comprises a pair of parallel members spaced apart to admit a spike, nail or other driven fastening, said members being connected in parallelism by transverse bolts or rivets which are arranged in staggered relation and whose inner surfaces form the walls of a tortuous passageway into which the spike is driven and by which it is distorted and its opposite walls given a sinuous or wavy form, and the inner walls of said members being, if desired, provided with bosses each of which is adapted to indent or press into one side of the spike to thereby displace the metal on the opposite side and form a projection which seats against the inner wall of one of the parallel members whereby the space between the inner walls of said parallel members and the corresponding walls of the spike may be so completely filled that lateral vibration of the spike is prevented and irregularities and variableness in the width of the space between the inner sides of said parallel members is compensated for without requiring the employment of separate filler pieces.

A further object of my invention is to provide a device of the type described, which may be cheaply made and which will be found effective as a nail or spike grip in attaching one piece to another.

With the above and other objects in view my invention consists of the parts, constructions, arrangements and combinations of parts which I will hereinafter describe and claim.

In the accompanying drawings forming part of this specification and in which similar reference characters indicate like parts in the several views;—Figure 1 is a sectional perspective view showing the application of my invention to a railway tie, or the like.

Fig. 2 is a longitudinal sectional view of the same. Fig. 3 is a cross-sectional view. Fig. 4 is a modification hereinafter described.

As the purpose of my invention is to provide a means whereby a spike, nail or equivalent part may be locked when driven into position, in a part having an opening or passageway prepared for it, it will be apparent that the invention will be found useful in various arts; it may, for instance, be used to advantage in the construction of railways as providing an effective means for securing a rail to a metallic tie. The invention may also be used in building constructions, for securing furring strips, or metal lathing, or as a means for suspending devices or articles of any character from a fixed support. It will be understood, therefore, that my invention has more or less general application and that it is not limited in its use to any particular field.

In Fig. 1 I have shown for illustrative purposes the application of my improvement to a railway tie. In this instance, the tie comprises two parallel members, A and B, formed of channel-iron, or the like, and which members are held in fixed spaced relation by means of suitable rivets, C, and spacing sleeves, D, on said rivets. The upper surfaces of the members, A and B, may form a seat for the ordinary railway rail, E, and which rail may be secured to the upper flanges of the parts, A and B, by any suitable means. In Fig. 1, I show the aforesaid flanges as being slotted and provided with outturned tongues, F, which are adapted to embrace and secure the base flanges of the rail. It will be understood, however, that other well known means may be adopted for seating the tie properly upon the rail. The rail, E, may be secured in its position by the spike, G, which spike is normally straight, but is adapted to be so distorted during the driving operation as to form an effective lock between itself and the tie.

The present invention relates to a specific means for distorting the spike simultaneously with the driving of the same, and to this end I employ suitable rivets, H, which are passed through the parallel members,

A and B, of the tie or other part and thence suitably headed, said rivets, H, being, arranged in staggered or alternating relation, whereby a tortuous passage is formed between the inner sides of the group of rivets forming the guideway or passage for the spike.

The spike or nail, whatever its particular cross-sectional shape, is normally substantially straight, but in the driving of the same this shape is designed to be simultaneously altered and certain of the opposite walls of the spike or nail are designed to be given a serpentine or sinuous form whereby the now substantially zig-zag spike becomes locked in the guideway formed by the group of staggered rivets, without the aid of other and supplemental fastenings.

In operation, the point of the nail is introduced into the space between the parallel members, A and B, forming the tie, in Fig. 1, and as the point of the nail successively engages the staggered rivets or bolts it is deflected first to one side and then the other, while the body of the spike is correspondingly curved, first in one direction and then in the other, as it is driven past and in contact with the inner surfaces of the rivets, so that when the spike is finally driven home, it will have had imparted to it a substantially serpentine form. The rivets also afford bearing points of substantial area at different points in the length of the spike and also give a positive or shoulder grip under the rivets, or the spacing sleeves thereon, by reason of the zig-zag course in which the spike is forced to travel while being driven fully to its seat, said spike being securely retained in place by the aforesaid distortion without requiring the use of supplemental fastenings. The staggered rivets also have the function of again straightening the spike when the same is withdrawn.

As there is likely to be some variableness in the width of the opening between the parallel members, A and B, and as the cross-sectional diameter of the nail or spike may not accord in all instances with the cross-sectional diameter of said space or opening, there will be afforded opportunity for lateral vibration of the spike after it has been driven into place, and to compensate for this irregularity or variableness and to secure the spike so that all possibility of transverse vibration may be avoided, I provide on the inner surfaces of the parallel members, A and B, suitable bosses, I, which may be represented by the heads of rivets and which are alternately disposed on the inner opposite walls of the members, A and B, and which bosses are also designed to distort the spike while the same is being driven into and through the tortuous passageway formed by the staggered rivets, H. By alternating the bosses, I, and not having them

disposed diametrically opposite each other, depressions, J, are formed in one side of the spike and corresponding projections, K, are offset from the opposite side for the purpose of filling any remaining space between the sides of the spike and the inner walls of the parallel members, A and B, whereby the spike is made to clearly fit the space between said members transversely and the spike is thus prevented from having any lateral or transverse vibration or movement and which movement is objectionable especially when the spike is used for securing a railway rail to a metal tie, or rail, where one part is designed to be so rigidly secured to another that lateral vibration would be a detriment.

To reduce the friction as much as possible due to the driving of the nail past the staggered rivets, I may provide the rivets with loose sleeves, L, which also serve as a means for holding the members, A and B, in parallel spaced relation.

The construction before specified will also be found useful as a means for securing furring strips or metal lathing in ceiling floor construction or for suspending any device from a fixed support above. In this instance, the members, A' and B', may represent a beam, as in Fig. 4, formed of parallel members connected by rivets, as before described, and the head of the spike may be employed for securing a furring or other piece, M, of whatever character; or the head may be made in the form of a hook, N, which will be found useful in suspending articles from the beam, which may represent any fixed support.

Various changes in the form, proportion and minor details of construction may be resorted to without departing from the principle, or sacrificing any of the advantages of the invention as claimed.

Having thus described my invention what I claim as new and desire to secure by Letters Patent is:—

1. A support formed of parallel spaced members, having a group of rivets extending transversely therethrough, and arranged in staggered relation to form a tortuous passage through which a driven member may be forced and simultaneously distorted and given substantially a sinuous form.

2. A support formed of parallel spaced members, having a group of rivets extending transversely therethrough and arranged in staggered relation to form a tortuous passage through which a driven member may be forced and simultaneously distorted and given substantially a sinuous form, and spacing sleeves loosely mounted on said rivets and directly engaged by said driven member.

3. A support formed of parallel spaced members having a group of rivets extending

transversely therethrough and arranged in staggered relation to form a tortuous passage through which a driven member may be forced and simultaneously distorted and given substantially a sinuous form, said members having bosses on their inner opposed surfaces, arranged in alternating relation and adapted to distort the driven member transversely during the driving thereof,

and form projections which engage the inner 10 surfaces of the members and thereby prevent lateral vibration of the driven member.

In testimony whereof I affix my signature in presence of two witnesses.

LAURENCE HUSTON KIRK.
